UNITED STATES PATENT OFFICE.

HANS DEUTSCH, OF VIENNA, AUSTRIA.

STEAM INJECTOR WITH AUTOMATIC SHIFTING VALVE.

Application filed February 9, 1925, Serial No. 7,898. Renewed November 19, 1925.

To all whom it may concern:

Be it known that I, HANS DEUTSCH, a citizen of Austria, and resident of Vienna, Austria, have invented certain new and useful Improvements in Steam Injectors with Automatic Shifting Valves, of which the following is a specification.

My invention relates to that type of steam injectors for locomotive engines which operate with live steam and exhaust steam while the engine proper is running so that a supply of exhaust steam is available. If the engine is standing still, or if it is running idle, so that no exhaust steam is produced, an injector of the type requiring both live steam and exhaust steam for its operation would cease to function under the conditions above referred to, when the supply of exhaust steam stops. My present invention relates to an improvement in injectors of the type mentioned, and has for its object to insure the proper operation of such an injector even when no exhaust steam is being supplied thereto. In order to accomplish this I provide a special novel arrangement whereby, when the supply of exhaust steam stops, an additional supply of live steam is brought into action automatically, this additional live steam being preferably in an expanded condition, that is to say, at a comparatively low pressure, corresponding substantially to the usual exhaust pressure. In the preferred form of my invention, an automatic valve is employed to control the shifting from one mode of operation (live steam combined with exhaust steam) to the other (live steam alone), and said valve is controlled by the pressure in the slide valve chest, the main steam pipe, or some other part receiving steam when the engine proper is in operation.

A typical and satisfactory example of my invention is illustrated by the accompanying drawing in longitudinal section.

Exhaust steam is admitted through the inlet 1 while high pressure live steam from the boiler reaches the inner or supplementary live steam nozzle 13 through a steam conduit 2. A portion of this nozzle is surrounded by an annular chamber 3 receiving at times steam under a reduced pressure from the auxiliary live steam conduit 4 in the manner set forth hereinafter. The outlet from the chamber 3 is annular, either as a slit, or as a series of openings surrounding

the nozzle 13, and is directed toward the exhaust nozzle 5, co-axial with the inner nozzle 13. In front of the nozzles 5 and 13 is the combining nozzle 14 receiving water from an inlet 15. Any excessive amount of water is discharged through an outlet 16 controlled by the overflow valve 17. The water is finally discharged through the delivery or pressure nozzle 18.

The inlet of the auxiliary live steam conduit 4 is controlled by an automatic valve 6 which in the position illustrated rests with its small lower end 7 upon a suitable seat in such a way as to close the entrance to the steam conduit 4. The upper end 8 of this valve is of larger diameter and is adapted to engage a corresponding upper seat. In the position illustrated, the live steam coming from the boiler through the inlet 10 has access to the auxiliary live steam conduit 2 and also to the upper face of the valve 6, through a pressure-reducing constricted opening 19 which leads into the chamber 20 containing the automatic valve 6. The automatic valve is thus balanced, and is held to its lower seat by gravity. This valve has an upward projection 6 adapted to engage a fluid pressure actuated member 12 located in a chamber 9 which by means of a conduit 11 communicates with the slide valve chest, the main steam pipe, or some other part in which a high steam pressure prevails while the engine proper is running. The member 12 which may be of any suitable construction, but which is shown as a valve is adapted, when held to its power position by steam pressure in the chamber 9, to prevent movement of the automatic valve to its upper position. The seating surface at the upper end 8 of the valve 6 may be roughened, or some other expedient may be adopted to produce a joint that will not be quite tight, so that even when the valve 6 is closed small amounts of steam will leak or pass from the chamber 20 to the chamber 9. Similarly, the seating surface of valve 12 may be constructed to allow a slight leakage, and furthermore, this valve may be moved off its seat by spring pressure so as to close only when the steam pressure in the chamber 9 exceeds a predetermined amount.

When the engine is proceeding under steam, a pressure more or less inferior to boiler pressure will exist in the chamber 9, since the latter is connected by the conduit

11 with the slide valve chest or with the steam pipe leading from the throttle valve to the slide valve chest and therefore the fluid pressure actuated member 12 will be 5 held to its lower position. The automatic valve 6 will, by the engagement of the lower face of the member 12 with the projection 6^a, also be held to its lower position to engage its lower seat and thus shut off the admission of live steam from the conduit 10 to 10 the conduit 4. During the injection of feed water, the full boiler pressure will exist at the inlet 10, and small amounts of steam will pass from this inlet through the opening 15 19 into the chamber 20, and from the latter through the narrow slit at the upper end of the shifting valve 6 into the chamber 9^a. From this chamber the steam will pass to the chamber 9, the valve 12 either being 20 slightly off its seat, or if seated, being constructed to allow leakage, as explained above. The injector under these conditions will operate with live steam flowing through 10, 12, 13 and with exhaust steam flowing from 1 25 to 5.

When the throttle of the locomotive is closed, so that the engine will run without steam, the pressure in the conduit 11 and chamber 9 will drop to such an extent that 30 the velocity of the steam flowing through the inlet 10 to the chamber 9 will be sufficient to lift the automatic valve 6 and bring it against its upper seat, because the upper end 8 of said valve is of larger seating surface 35 than its lower end 7. With the automatic valve 6 in its upper position, the chamber 20 will be placed in communication with the auxiliary live steam conduit 4, so that live steam will pass through the conduit 4 as 40 well as through the conduit 2. In this case the injector will work with live steam alone, the steam flowing through the conduit 4 having the same function as previously performed by the exhaust steam. If, as suggested above, the valve 6 or its upper seat 45 are so constructed as to permit leakage when the valve is seated upwardly, or if other means are provided to obtain a leak or "bleeding" action, small amounts of steam 50 will pass from the chamber 9^a to the chamber 9 and thence through the conduit 11 to the slide valve chest. Such steam is wasted, but the amount of waste is so small as to be immaterial in its effect on the efficiency of the 55 injector.

It is important to reduce the pressure of the steam passing through the auxiliary live steam conduit 4, before such steam reaches the nozzles. In the specific example illustrated, this reduction is obtained by throttling the live steam at the opening 19, before such steam reaches the automatic valve 6 controlling the inlet of the conduit 4. Under these conditions, with the valve lifted against its upper seat, the pressure in chamber 20

will be comparatively low, and thus, when the engineer again opens the throttle valve, a relatively low pressure in the slide valve chest will suffice to enable the fluid pressure member 12 to press the automatic valve 6 70 against its lower seat, thereby cutting off the supply of steam to the auxiliary live steam conduit 4.

Various modifications may be made without departing from the nature of my invention as set forth in the appended claims. 75

I claim:

1. An apparatus of the class described, comprising a valve chamber and means for connecting said chamber with a part containing steam substantially under boiler pressure only when the engine is in operation, a valve located in said chamber and adapted to be urged toward its seat by such pressure, an inlet for high pressure steam, a nozzle in permanent communication with said inlet, an inlet for exhaust steam, a second nozzle in permanent communication with said exhaust inlet, a conduit for conveying high pressure steam coming from the high pressure steam inlet to said second nozzle, a second chamber the communication of which with the first named chamber is controlled by said valve, and a shifting valve having seating surfaces of different sizes, the larger seating surface controlling the communication of said second chamber with the high pressure steam inlet, while the smaller seating surface of said shifting valve controls the communication of said high pressure steam inlet with the conduit leading to said second nozzle, whereby the shifting valve will be seated on its larger seating surface whenever the high pressure prevailing at the high pressure steam inlet exceeds by a predetermined amount, the pressure existing in the first mentioned valve chamber, thereby admitting high pressure steam to said second nozzle, whereas in the absence of such pressure difference the shifting valve will shut off high pressure steam from said second nozzle. 100

2. An apparatus of the class described, comprising a valve chamber and means for connecting said chamber with a part containing steam substantially under boiler pressure only when the engine is in operation, a valve located in said chamber and arranged to be seated by said pressure, a shifting valve having seating surfaces of different sizes, the larger seating surface facing the first named valve, and the shifting valve, when seated on such larger seating surface, forming a stop for the first named valve to prevent the latter from becoming seated, an inlet for boiler steam, a nozzle in permanent communication with said inlet, an inlet for exhaust steam, a second nozzle in permanent communication with said exhaust inlet, and a conduit for leading live steam to said 115 120 125 130

second nozzle, the communication of said conduit with the boiler steam inlet being controlled by the small end of said shifting valve.

3. An apparatus of the class described, comprising a valve chamber having a connection for supplying steam under pressure, a valve in said chamber, arranged to be seated by such pressure, a shifting valve having a relatively large seating surface at one end and a relatively small seating surface at the other end, the end with the larger seating surface being directed toward the first named valve, and the shifting valve, when seated with its larger end, forming a stop to prevent the first-named valve from becoming seated, an inlet for high pressure steam, an injector nozzle in permanent communication with said inlet, an inlet for exhaust steam, a second nozzle in permanent communication with said exhaust inlet, and a conduit for leading the high pressure steam to said second nozzle, the communication of said conduit with the high pressure steam inlet being controlled by the small end of said shifting valve, and means whereby the pressure of the steam flowing from the high pressure inlet to said second nozzle through said conduit will be reduced before such steam reaches this nozzle.

4. An apparatus of the class described, comprising a valve chamber and means for connecting said chamber with a part containing steam substantially under boiler pressure only when the engine is in operation, a valve located in said chamber and adapted to be urged toward its seat by such pressure, an inlet for high pressure steam, a nozzle in permanent communication with said inlet, an inlet for exhaust steam, a second nozzle in permanent communication with said exhaust inlet, a conduit for conveying high pressure steam coming from the high pressure steam inlet to said second nozzle, a second chamber the communication of which with the first named chamber is controlled by said valve, and a shifting valve having seating surfaces of different sizes, the larger seating surface controlling the communication of the said second chamber with the high pressure steam inlet, while the smaller seating surface of said shifting valve controls the communication of said high pressure steam inlet with the conduit leading to said second nozzle, whereby the shifting valve will be seated on its larger seating surface whenever the high pressure prevailing at the high pressure steam inlet exceeds by a predetermined amount, the pressure existing in the first mentioned valve chamber, thereby admitting high pressure steam to said second nozzle, whereas in the absence of such pressure difference the shifting valve will shut off high pressure steam from said second nozzle, said shifting valve,

when seated on its larger seating surface, forming a stop to prevent the first named valve from becoming seated.

5. An apparatus of the class described, comprising a valve chamber having a connection for supplying steam under pressure, a valve in said chamber, arranged to be seated by such pressure, a shifting valve having a relatively large seating surface at one end and a relatively small seating surface at the other end, the end with the larger seating surface being directed toward the first named valve, and the shifting valve, when seated with its larger end, forming a stop to prevent the first-named valve from becoming seated, an inlet for high pressure steam, an injector nozzle in permanent communication with said inlet, an inlet for exhaust steam, a second nozzle in permanent communication with said exhaust inlet, and a conduit for leading the high pressure steam to said second nozzle, the communication of said conduit with the high pressure steam inlet being controlled by the small end of said shifting valve, and means for throttling the high pressure steam on its way from the high pressure steam inlet to said conduit, before such steam reaches the shifting valve.

6. The combination with an exhaust steam injector having conduits connected therewith for supplying exhaust steam, supplementary live steam and auxiliary live steam to said injector, of an automatic valve for controlling the admission of live steam to said auxiliary conduit, and a connection from a source of live steam, said automatic valve being interposed between said connection and said auxiliary live steam conduit to be operated by the steam passing to said auxiliary conduit.

7. The combination with an exhaust steam injector having conduits connected therewith for supplying exhaust steam, supplementary live steam and auxiliary live steam to said injector, of an automatic valve for controlling the admission of live steam to said auxiliary conduit, and a connection from a source of live steam, said automatic valve being interposed between said connection and said auxiliary live steam conduit to be operated by the steam passing to said auxiliary conduit, said automatic valve being further provided with a restricted passageway between said connection and said auxiliary live steam conduit to throttle the live steam.

8. The combination with an exhaust steam injector having conduits connected therewith for supplying exhaust steam, supplementary live steam and auxiliary live steam to said injector, of a valve casing having an inlet adapted to be connected to a source of live steam, and a pair of outlets connected to said supplementary and auxiliary live steam conduits, a fluid pressure actuated

means in said casing connected with a steam line of the engine, and a valve in co-operative relationship with said fluid pressure means, and movable to either of two positions in one of which it permits communication between said inlet and auxiliary live steam conduit, and in the other of which positions, it shuts off such communication, the movement of said valve being automatically accomplished by the steam passing to said auxiliary live steam conduit and being controlled by the position of said fluid pressure means.

9. The combination with an exhaust steam injector having conduits connected therewith for supplying exhaust steam, supplementary live steam and auxiliary live steam to said injector, of a valve casing having an inlet connected with a source of live steam, and outlets connected to said supplementary and auxiliary live steam conduits, a valve mounted in said casing and movable to either of two positions, in one of which it permits the steam to flow to said auxiliary live steam conduit and in the other prevents such flow, a fluid pressure actuated means in juxtaposition to said valve, and a connection between said fluid pressure means and a steam line of the engine for causing the movement of said valve to be automatically controlled in accordance with the pressure conditions in said steam line.

10. The combination with an exhaust steam injector having conduits connected therewith for supplying exhaust steam, supplementary live steam and auxiliary live steam to said injector, of a valve casing having an inlet connected with a source of live steam, and outlets connected to said supplementary and auxiliary live steam conduits, a valve mounted in said casing and movable to either of two positions, in one of which it permits the steam to flow to said auxiliary live steam conduit, and in the other prevents such flow, the pressure of the steam within said casing flowing to said auxiliary conduit normally tending to move said valve to said first named position, a fluid pressure actuated means adjacent to said valve, and a connection from a steam line of the engine to said means for causing said fluid pressure means to hold said valve in said other position when steam under pressure is present in said steam line.

11. A combination as set forth in claim 10, in which the valve casing is provided with a restricted opening between said inlet and the outlet for said auxiliary live steam conduit to throttle the pressure of the live steam passing to said conduit.

In testimony whereof I have hereunto set my hand.

HANS DEUTSCH.
